UNITED STATES PATENT OFFICE.

FRANK PINK, OF PORTSMOUTH, ENGLAND.

APPARATUS FOR SEPARATING LIQUIDS OF DIFFERENT SPECIFIC GRAVITY.

Application filed January 26, 1925, Serial No. 4,830, and in Great Britain March 20, 1924.

The present invention relates to apparatus for separating liquids of different specific gravity.

In apparatus for carrying out separation of liquids of different specific gravity as described in my prior application Serial No. 697,960, filed 8th March 1924 it has been proposed to allow the heavier liquid to continuously flow therethrough while the lighter liquid has been discharged or withdrawn intermittently.

According to the present invention apparatus of the kind described in my prior application aforesaid is modified to provide for the separation of liquids of different specific gravity wherein the lighter liquid or a lighter liquid is the continuous flow liquid and the heavier liquid is discharged or withdrawn intermittently through a valve device.

The discharge or withdrawal of the heavier liquid may be automatically controlled by, for example, the level of the heavier liquid. Or the heavier liquid may be withdrawn by a manual operation of the valve device under guidance of an indicator shewing the respective levels of the lighter and heavier liquids.

The accompanying drawings illustrate diagrammatically two forms of apparatus according to the present invention, the discharge or withdrawal of the heavier liquid being automatically controlled by the level of the heavier liquid.

Fig. 1 is a side view, Fig. 2 a plan view with the top plate removed and Fig. 3 an end view of one form of apparatus, while Figs. 4 and 5 are side and plan views respectively of another form of apparatus.

As shewn in Figs. 1 to 3 inclusive of the drawings there is provided a closed chamber 1, having baffles 2 stopping short of the top and bottom of the tank. An inlet 3 for the mixture is provided at one end. At the other end and at or adjacent the top of the chamber is an outlet 4 for the lighter liquid and at the bottom of the chamber and at the inlet mixture end is a heavier liquid outlet 5 located in a well or float chamber

6. The outlet 5 has a valve control, as for example an automatically operated valve 7, under a float control 8, a lever connection 9 being interposed between the valve 7 and the float 8. Heating devices, such as steam

coils 10 and 11 may be provided in the 55 chamber 1.

The chamber 1 has a sloping bottom 1^a, the slope being towards the well or float chamber 6.

In practice the chamber 1 is first filled 60 with water up to the datum line D—D and thereafter filled with oil.

The mixture (oil and water) enters at 3 and passes over baffles to the outlet 4. The water in mixture falls between the baffles 65 2 to bottom of chamber and eventually collects in well or float chamber 6. When sufficient water has collected above the datum line D—D to operate the float 8 this rises and opens the discharge valve 7 through the 70 lever connection 9. The water then discharges through the valve 7 until the level of the water in the well or float chamber 6 sinks to the datum line D—D when the valve 75 closes due to the sinking of the float 8.

The heavier liquid valve may be of the float type which is let down by the lighter liquid and floated by the heavier liquid.

Now referring to Figs. 4 and 5 of the accompanying drawings this shews a form 80 of apparatus which is well suited for inclusion in a gas works plant as a component. With this form it is possible to separate out three constituents of a mixture.

This form of separator is divided into two 85 compartments 12 and 13. The mixture is led into the compartment 12 by a path 14, 15. Assuming the separator as a unit in a gas works plant in the compartment 12 light oil is discharged at 16. The heavy oil and 90 water passes from the compartment 12 by way of the communicating passage 17. The heavy oil (tar) is then removed at 18 and the water at 19. As indicated the discharge 19 may communicate at 20 with a filter 21, 95 or the water may be discharged through 22 unfiltered. Baffles 2 may be provided in both compartments 12 and 13. A float 8 controls the opening and closing of the discharge 18. The discharge 16 may have a 100 manually or automatically operated valve.

In the forms shewn the float may not be directly connected to the valve but mechanical or electrical devices, controlled for actuation by movement of the float, may be 105 used for operating the opening or closing of the valve.

Mechanical or electrical devices of the

kind set out in my aforesaid application may be used or modified for use with apparatus according to the present invention.

What I claim is:—

- 5 1. An apparatus for separating liquids of different densities of the kind referred to comprising a horizontally elongated closed vessel into which the mixture enters, a mixed liquid inlet located at one end of the vessel
10 and an outlet for the lighter liquid located remote from said inlet, the mixed liquid having an unrestricted substantially horizontal flow through the vessel from inlet to exit and the lighter liquid being under continuous flow, a
15 discharge chamber for the heavier liquid located at the bottom of said vessel and at one end thereof, an outlet for the heavier liquid in said discharge chamber, and means controlling the opening and closing of said heavier liquid outlet, said means comprising a valve proper, a float, and a lever connection between the valve and the float, said valve functioning to automatically open said outlet when there is an accumulation of the
20 heavier liquid in the immediate vicinity thereof, and to automatically close said outlet when there is an accumulation of the lighter liquid in the immediate vicinity thereof.
25

- 30 2. An apparatus for separating liquids of different densities of the kind referred to, comprising a vessel of horizontal elongated form into which the mixture enters, an inclined way extending from end to end of said vessel, co-acting baffle plates of varying length disposed in proximity to said inclined way, a mixed liquid inlet located at one end of the vessel and an outlet for the lighter liquid located remote from said inlet, the mixed liquid having an unrestricted substantially horizontal flow through the vessel from inlet to exit and the lighter liquid being under continuous flow, a discharge chamber for the heavier liquid located at the bottom of said vessel and at one end thereof, an outlet for the heavier liquid in said discharge chamber, and a control valve for said heavier liquid outlet functioning to automatically open said outlet when there is an accumulation of the heavier liquid in the immediate vicinity thereof, and to automatically close said outlet when there is an accumulation of the lighter liquid in the immediate vicinity thereof.
- 35 40 45 50

In testimony whereof, I affix my signature.

FRANK PINK.
